(57) **CLAIM**

The ornamental design for an electrical sensor conductor pattern, as shown and described.

DESCRIPTION

FIG. 1 is a top isometric view of an electrical sensor conductor pattern showing our new design.

FIG. 2 is a top plan view thereof, the bottom plan view being identical, thereto; and,

FIG. 3 is a side elevation thereof, with all other sides being identical thereto.

The broken lines shown in FIGS. 1 and 2 are for illustrative purposes only and form no part of the claimed design.
